UNITED STATES PATENT OFFICE.

ALBERT E. JOHNSON, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR MAKING INSOLES.

1,252,348.

Specification of Letters Patent. Patented Jan. 1, 1918.

Application filed May 8, 1912. Serial No. 694,814.

To all whom it may concern:

Be it known that I, ALBERT E. JOHNSON, a citizen of the United States, residing at Beverly, in the county of Essex and State 5 of Massachusetts, have invented certain new and useful Improvements in Machines for Making Insoles; and I do hereby declare the following to be a full, clear, and exact description of the invention, such as will enable others skilled in the art to which it 10 appertains to make and use the same.

The present invention relates to machines for making insoles to be used in the manufacture of boots and shoes.

15 The object of the invention is to produce a machine for performing various steps in the making of regular welt insoles. With this object in view a feature of the invention contemplates the provision, in a machine for 20 making insoles, of simplified and improved devices for setting the lip. Other features of the invention consist in improved devices for beveling the edge of the unlined face of the insole, in an improved construction and 25 arrangement of the knife lifting mechanism by which the knives are cut out of the stock of the sole at the breast line, and in certain devices, combinations and arrangements of parts tending to improve and simplify the 30 operation of machines for making insoles. The advantages of these devices, combinations and arrangements of parts will be obvious to those skilled in the art from the following description.

35 Preferably the features of the present invention are embodied in a machine having the same general construction and arrangement of parts as the machine disclosed in Letters Patent of the United States issued 40 to United Shoe Machinery Company on an application of William C. Meyer, No. 984,773, dated February 21, 1911.

In the drawings illustrating the preferred embodiment of the invention,

45 Figure 1 is a rear elevation of the machine;

Fig. 2 is a left side elevation;

Fig. 3 is a detail in rear elevation, partly in section, showing the operating position 50 of the tools;

Fig. 4 is a detail in left side elevation, partly in section, showing the operative connection between the vertically reciprocating hammer and its oscillating actuator;

Fig. 5 is a plan of the parts illustrated in 55 Fig. 3;

Fig. 6 is a detail in right side elevation illustrating the manner in which the knives leave the work;

Fig. 7 is a graphical representation of 60 the manner in which the knives leave the work; and

Fig. 8 is a perspective view of the insole beveling knife.

In the illustrated embodiment of the invention the construction and mode of operation of the channel knife 1, edge knife 2, presser foot 3, four-motion feed foot 4 with its spring 114, work support 5, and edge gage 6 with its adjusting mechanism 116, 65 are substantially identical with the construction and mode of operation of the same parts in the machine disclosed in the above mentioned patent with the following exceptions; namely, the channeling knife 1 is adapted to 70 form, as shown in Fig. 3, the usual welt insole channel, and the presser foot 3 is bifurcated (see Figs. 3 and 5) to form a channel knife presser foot 7 and an edge knife presser foot 8. 80

As shown more particularly in Figs. 3, 4 and 5, the angular construction of the shank of the edge knife 2 is such that it acts as a plow to raise the lip cut by the edge knife into a substantially vertical position. In 85 order to set the lip, the machine illustrated in the drawings is provided with a hammer 9 which has a curved face 10 for initially bending the upturned lip over toward the between substance and a flat face 11 for hammering the bent lip down upon the between substance. The hammer 9 is carried by the lower end of a vertical spindle 12 slidably mounted, for movement in a path normal to the sole face, in a bore formed in the usual vertically movable, spring pressed knife carrier or slide 13 for the knives and presser feet. The hammer is normally maintained elevated from the work, so as to permit the sole to be fed and the up-turning of 90 100

the lip, by a light spring 14 coiled around the spindle 12 and interposed between a shoulder 15 formed by an opening in the slide 13 and a transverse pin 16 carried by the spindle. During the operation of the machine the hammer is vertically reciprocated against the tension of the spring 14, to set the lip, through an operative connection with a hammer arm or actuator 17 mounted to oscillate about a horizontal stud 18 carried by the knife slide 13. When so mounted, the hammer actuator oscillates across the line of feed, or, stated more broadly, moves in a path at substantially right angles to the path of movement of the hammer. The hammer is operatively connected to the actuator 17 by a dog 19 pivotally mounted on a block 20 suitably secured to the lower end of the actuator 17. The dog 19 is provided 20 with a body portion arranged to engage the upper face of the hammer 9 and with a nose 21 arranged to engage a wall 22 formed on the hammer. The nose of the dog is held continuously engaged with the wall of the hammer by a light spring 23, one end of which is secured to the block 20, and the other end of which is secured to the dog 19. The actuator 17 is connected through a rod 24 to a cam lever 25 pivoted at one end to the machine frame and provided at its other end with a roll engaging a cam groove 26 formed in the periphery of a drum 27 secured to a driving shaft 28. As the actuator 17 is swung about the horizontal stud 18 to actuate the hammer the block 20 is moved downwardly and inwardly or toward the left (viewing Fig. 1), but as the dog 19 is prevented from movement toward the left by the engagement of its nose with the wall 22, 30 the inward movement of the block causes the dog to turn downwardly about its pivotal connection with the block against the tension of its spring 23. This movement of the dog actuates the hammer downward so as to 35 strike a blow upon the lip. In order to vary the force of the blow of the hammer upon the work, the rod 24 is provided with a turn-buckle 29. By manipulating this adjustable connection between the cam groove 26 and the actuator 17, the normal inoperative position of the hammer above the work may be varied as desired. As the hammer is moved downward a uniform distance a variation of 40 its normal height above the work either varies the force of the blow of the hammer upon the work or prevents the hammer from striking the work.

It is desirable to bevel the edge of the unlined face of a welt insole for a purpose 45 well known to those skilled in the art, and therefore the present machine has been provided with a beveling knife which, as shown in Figs. 1, 3 and 5, is secured upon the upper side of the edge gage 6. As shown, the

beveling knife is provided with a shank 30 65 having an angular offset 31 (Fig. 5) which passes at an acute angle through a slot 32 in the edge gage finally terminating in a cutting edge 33 arranged to bevel the edge of the unlined face of the insole. 70

In beveling the edge of the unlined face of an insole it is highly desirable that the beveling knife act with certainty in removing the skiving from the edge of the sole. To this end the lower end of the beveling knife is provided with a thin, tapered foot 34 (see Fig. 8) which is interposed between the sole engaging surface of the work support and the unlined face of the sole. The foot 34 maintains the relative position of the edge of the unlined face of the sole and the cutting edge 33 uniform and thus insures the complete severance of the bevel string. 75

As is well known to those skilled in the art, because of its curvature the lip at the shank is difficult to turn up. This difficulty is usually obviated by cutting transverse slashes in the lip at the shank by hand to permit the lip turning tool to perform its turning operation upon successive short sections of the lip at the shank. In order to permit the easy turning up of the lip at the shank, the feed foot 4 in the machine of the drawings, is provided with a laterally extending knife 35 (Figs. 2, 3, 5 and 6) which, as the foot engages the work preparatory to the feeding stroke, cuts a transverse slash in the margin of the insole in advance of the operation of the edge knife 2. Preferably 90 the depth of the transverse slash is the same as the thickness of the lip. The slashing knife extends from the feed foot in such position that while the machine is operating around the forepart of the sole where the feather is relatively narrow, it strikes outside the edge of the sole when the feed foot moves downward (see Fig. 5). As shown in Fig. 5 the cutting blade of the slashing knife 35 is of such width as to extend only 95 partially across the cutting edge of the edge knife 2. With this construction, when the edge gage 6 is set for a narrow feather around the forepart the relation of the sole to these two knives is such that while the edge knife remains active the slashing knife is rendered inactive. When the edge gage is retracted, however, to channel the shank of the sole, the movement of the sole inward 100 relative to the feed foot to retain a bearing against the gage is sufficient to permit the slashing knife to engage and slash the margin of the sole throughout the shank. The lip, cut at the shank, is thus divided into a series of short sections thereby facilitating 105 the operations of turning it up. 110

In order to avoid weakening the heel seat it is desirable, in channeling insoles, to stop

the cutting of the knives at a point about opposite the breast line of the heel. To this end the knife slide 13 is provided with a rack 36 which meshes with a segment 37 formed on one end of an arm 38 pivoted on the machine frame. The other end of the arm 38 is connected to a rod 39 having a lost motion connection with a rod 40 connected to a treadle 41 pivoted on the machine frame. The lost motion connection between the rods 39 and 40 consists of a block 42 (Fig. 2) secured to the rod 39 and loosely embracing the rod 40. The upper end of the rod 40 is provided with a set of adjusting and lock nuts 43 which serve to limit the amount of lost motion in the connection between the rods 39 and 40. The treadle is also connected to the work support 5 by a chain 44, one end of which is attached to the usual work support lowering toggle, and the other end of which is attached to the treadle 41. A few links of the chain are normally held slack by a coiled spring 45, the opposite ends of which are secured to separated links of the chain (Fig. 2). The knife slide is thus relieved of the weight of the treadle and the rod 40 which permits the use of a light spring for holding the knives to their work and the production of a uniform thickness of channel flap and lip. With the construction described, when it is desired to stop the cutting of the knives, the treadle is depressed until the lower nut 43 rests upon the block 42. This movement of the treadle elevates the knife slide slightly, at the same time straingtening the chain 44 without, however, lowering the work support. As the knives are embedded in the work, the insole is raised from the work support when the knife slide is elevated. The feed foot 4 now descends under the pressure of its spring and digs into the insole preparatory to a feeding step. Owing to the hold of the knives in the work, the insole is prevented from being stripped from the knives under the pressure of the feed foot spring. This is represented graphically in Fig. 7, where the arrow A represents the pressure of the feed foot spring 114 and the arrow B represents the pressure of the feed foot in feeding the insole for the cut of the knives. During the feed the feed foot spring constantly tends to vertically depress the insole while the feed foot is moving the insole in a horizontal plane. The resultant of the pressures A and B is represented graphically by the arrow C in Fig. 7. The knives are thus caused to leave the work diagonally in the line of feed (Fig. 6), whenever the knife slide is elevated in the manner described. A further depression of the treadle now completes the elevation of the knife slide and simultaneously lowers the work support to permit the ready removal of the

finished insole and the insertion of a fresh 65 blank.

From the foregoing description it will be obvious to those skilled in the art that the feature of the invention which contemplates improved mechanism for cutting out the 70 knives is adapted for use in making the leather bodies of insoles intended for reinforcement whether the machine is fitted for making one or two lips. It will also be obvious that the feature of the invention which 75 contemplates the setting of the lip is not dependent for its usefulness on a combination with lip forming devices, but can be employed in setting the lip of a previously 80 channeled insole.

It will be clear to those skilled in this class of machines and with the general objects of the present invention in view, that changes may be made in the details of structure, the described and illustrated embodiment of the invention being intended as an exploitation of its underlying essentials, the features whereof are definitely stated in their true scope in the claims herewith. 90

What is claimed as new, is:—

1. A machine for making insoles, having, in combination, a lip forming knife, a slide for said knife provided with a horizontal stud, a hammer for engaging and setting the lip upon the face of the insole, and a 95 hammer arm for actuating the hammer arranged to oscillate on the horizontal stud, substantially as described.

2. A machine for making insoles, having, in combination, means for cutting and upturning a lip from the substance of the insole, a hammer reciprocable toward and from the sole face to engage and set the lip upon the face of the insole, a hammer actuator mounted to move in a path at 100 substantial right angles to the movement of the hammer, means for operating the actuator, and means carried by the hammer actuator for engaging and reciprocating the hammer, substantially as described. 105

3. A machine for making insoles, having, in combination, means for cutting and upturning a lip and a flap from the substance of the insole, means for feeding the insole, a hammer reciprocable toward and from the sole face to engage and set the lip upon the 110 between substance, a hammer actuator, means to oscillate said actuator across the line of feed, and an operative connection between the actuator and hammer for reciprocating the latter, substantially as described. 115

4. A machine for making insoles, having, in combination, a lip forming knife, an edge gage movable to vary the position of the sole edge with relation to the lip forming knife, and a knife movable with the edge gage provided with a cutting edge for bevel- 125

ing the edge of the unlined face of the sole and with a foot arranged to engage the unlined face of the sole for insuring the severance of the bevel string, substantially as described.

5. A machine for making insoles, having, in combination, a lip forming knife, means for feeding the insole, and mechanism for causing the knife to leave the work diagonally in the line of feed during the feed, substantially as described.

6. A machine for making insoles, having, in combination, a lip forming knife, a four-motion insole feeding device, and mechanism 15 for causing the knife to leave the work diagonally under the influence of the feeding device, substantially as described.

7. A machine for making insoles, having, in combination, a work support, a knife 20 carrier arranged to move in a straight slideway above the work support, and a single means for concurrently elevating the carrier in its slideway and lowering the work support, being arranged to initially elevate 25 the knife carrier in advance of the initial lowering of the work support, substantially as described.

8. In a machine for making insoles having, 30 a marginal lip formed by cutting inwardly from its edge portion, a hammer for engaging and setting the lip, an independently mounted hammer arm for actuating the hammer arranged to oscillate about a horizontal axis located above the work, and an operative connection between the hammer arm and hammer, substantially as described.

9. In a machine for making insoles, the 40 combination of a hammer constrained to slide toward and from the sole face in a right line path normal thereto, an independently mounted oscillating actuator, and an operative connection between the actuator and the hammer for reciprocating the hammer, substantially as described.

10. In a machine for making insoles, the 50 combination of a slideable hammer for setting the lip, a spring normally holding said hammer away from the lip, an independently mounted actuator adapted to engage the hammer and intermittently advance it toward the lip against the force of said spring, and means for operating the actuator, substantially as described.

55 11. In a machine for making insoles, the combination of a hammer constrained to slide toward and from the sole face, an independently mounted oscillating actuator, and an operative connection between the actuator and the hammer for reciprocating the hammer comprising a dog pivotally mounted on the actuator and arranged to engage the hammer, substantially as described.

12. In a machine for making insoles, the

combination of a hammer, provided with 65 a wall, constrained to slide toward and from the sole face, an independently mounted oscillating actuator, and an operative connection between the actuator and the hammer for reciprocating the hammer comprising 70 a dog yieldingly mounted on the actuator and provided with a nose arranged to engage the wall on the hammer, substantially as described.

13. In a machine for making insoles, a lip 75 setting device comprising a hammer constrained to slide toward and from the sole face, a hammer actuator mounted to move in a path at substantial right angles to the movement of the hammer, means carried by 80 the actuator for engaging and reciprocating the hammer, and means for operating the actuator, substantially as described.

14. In a machine for making insoles, a lip 85 setting device comprising a hammer actuator movable across the sole face, a hammer movable toward and from the sole face in a right line path normal thereto, and connections between said hammer and actuator for operating the former from the latter, substantially as described.

15. In a machine for making insoles having, 95 a marginal lip formed by cutting inwardly from its edge portion, a hammer movable in a path normal to the sole face for engaging and setting the lip, a hammer actuator comprising an arm extending substantially parallel to the path of movement of the hammer and movable toward and from the lip, and an operative connection between the actuator and hammer, substantially as described.

16. A machine for making insoles, having, 105 in combination, a lip forming knife, and a beveling knife arranged to act on the edge of the unlined surface of the sole, said beveling knife being provided with a foot to engage the sole and insure the severance of the bevel string, substantially as described.

17. A machine for making insoles, having, 110 in combination, a lip forming knife, a slide for said knife, a hammer movably mounted in said slide in position to engage the lip, a hammer actuator, an operative connection between the actuator and the hammer for operating the hammer to set the lip, and means for operating the actuator, substantially as described.

18. A machine for making insoles, having, 120 in combination, an edge knife for slitting the sole edge to produce a marginal lip, an edge gage adjustable to advance it transversely relative to said edge knife to decreaseably vary the width of cut, and a knife 125 for making transverse slashes each of uniform depth throughout its length in the marginal portion of the insole so arranged relatively to the edge knife as to become in-

active when the edge gage is adjusted to greatest advance position, substantially as described.

19. A machine for making insoles, having, in combination, an edge knife for slitting the sole edge to produce a marginal lip, and a coöperating knife for producing a transversely slashed lip having its cutting blade extending only partially across the cutting edge of said edge knife, where-

by when the sole is moved transversely beneath said knives to decrease the width of edge slit the slashing knife will be positioned entirely outside of the sole and thus be rendered inactive, substantially as described. 15
